Primary Examiner — Darcey E Gottschalk*Assistant Examiner* — Bailey M Knotts(74) *Attorney, Agent, or Firm* — Notaro, Michalos & Zaccaria P.C.(57) **CLAIM**

The ornamental design for a fan light as shown and described.

DESCRIPTION

FIG. 1 is a front bottom perspective view of a fan light showing the design;

FIG. 2 is a front side view thereof;

FIG. 3 is a rear side view thereof;

FIG. 4 is a right side view thereof;

FIG. 5 is a left side view thereof;

FIG. 6 is a bottom plan view thereof; and,

FIG. 7 is a top plan view thereof.

The broken lines represent portions of the fan light that form no part of the claimed design.
